LOCK

Edward N. Jacobi, Milwaukee, Wis., assignor to
 Briggs & Stratton Corporation, Milwaukee,
 Wis., a corporation of Delaware

Application March 30, 1940, Serial No. 327,042

7 Claims. (Cl. 70—431)

This invention relates to locks, and refers particularly to cylinder locks of the type used in automobile door and deck handles.

It is now common practice to mount cylinder locks in the stems of automobile door handles. It is also customary to die-cast the handles as well as the lock cylinders; and while this method of manufacture is quite accurate, dimensional discrepancies are inevitable. Thus, to insure proper freedom of operation for the cylinder, substantial clearance must be provided between the cylinder and the walls of the bore in which it is mounted.

These irregularities often result in the lock cylinder head lying against one side of the bore or hole in which it is received and leaving a rather wide crack at the opposite side into which water flows to freeze in winter and cause corrosion in other seasons. This difficulty is particularly prevalent when the lock is mounted in the deck handle of an automobile where it is more apt to catch rain and wash water.

While so-called dust covers have been used to guard against the entrance of dirt and foreign matter into the keyhole of the lock and sometimes extend beyond the edge of the cylinder for the purpose of excluding extraneous matter from the space between the cylinder and its bore, these past constructions could not be made with sufficiently close fitting parts to actually insure against the entrance of water into the space between the cylinder and its bore.

It is, therefore, the primary object of this invention to provide a lock having means incorporated therein specifically designed for and capable of sealing the mouth of the cylinder bore against the entry of water.

More specifically, it is an object of this invention to provide a seal at the mouth of the bore in which the cylinder is mounted which, by virtue of its novel construction, accommodates the slight irregularities incident to diecast production and at all times insures a close fit between the relatively movable parts to prevent the entry of water and other foreign matter into the clearance space between the cylinder and bore walls.

Another object of this invention is to provide a seal of the character described which is maintained by means of a spring mounted within the structure of the lock itself.

With the above and other objects in view, which will appear as the description proceeds, this invention resides in the novel construction, combination and arrangement of parts substantially as hereinafter described and more particularly

defined by the appended claims, it being understood that such changes in the precise embodiment of the herein disclosed invention may be made as come within the scope of the claims.

The accompanying drawing illustrates one complete example of the physical embodiment of the invention constructed according to the best mode so far devised for the practical application of the principles thereof, and in which:

Figure 1 is a view partly in side elevation and partly in longitudinal section through an automobile door handle equipped with a lock constructed in accordance with this invention;

Figure 2 is a detail view at right angles to Figure 1 with part thereof broken away and in section; and

Figure 3 is a perspective view of the sealing member per se.

Referring now particularly to the accompanying drawing, in which like numerals indicate like parts, the numeral 5 designates the handle of an automobile door or deck which in conformance with general practice is a die-casting formed with a bore 6 and provided with a tubular extension 7 secured in its inner end. At the mouth of the bore 6 is a counterbore 8, and the extension 7 has a transverse bore 9 therethrough.

Mounted in the bore of the handle is a lock cylinder 10 of conventional construction having tumblers 11 projectable into longitudinal tumbler receiving grooves 12 opening to the bore. The tumblers are retractable within the confines of the cylinder upon the insertion of a proper key into the keyway of the cylinder, to free the cylinder for rotation.

Rotation of the cylinder is utilized to retract and project a locking bolt 13 mounted in the cross bore 9 and by which the handle is secured against rotation. Cylinder rotation is translated into reciprocation of the bolt 13 through a crank pin 14 projecting eccentrically from the inner end of a stem 15 carried by the cylinder.

As stated, the handle 5 is generally a diecasting. The lock cylinder is also generally a diecasting, but the extension 15 is of stronger metal cast into the inner end of the cylinder.

Although the diecasting method of production provides fair accuracy, dimensional discrepancies are inevitable and consequently substantial clearance must be provided between the cylinder walls and the walls of the bore. This clearance should be closed against the ingress of water and dirt.

To this end, a sealing ring 16 is secured in the counterbore 8. This sealing ring has a cylindrical wall 17 adapted to have a press fit in the

counterbore and an annular inwardly directed flange 18 which overlies the outer rounded face of an enlarged head 19 on the outer end of the cylinder.

- 5 Firm engagement between the undersurface of the flange 18 and the outer rounded face of the cylinder head is assured and maintained by a compression spring 20 coiled about the cylinder extension 15 and confined between the inner end 10 of the cylinder and a shoulder 21 serving as a bottom for the bore and provided in this instance by the inner end of the tubular extension 7.

The spring 20 yieldingly urges the lock cylinder outwardly and thus holds the outer end thereof 15 firmly against the underside of the flange 18.

To insure as complete a seal as possible, the inturned annular flange 18 is reduced in thickness toward its inner periphery to give the same a feather-edged formation of sufficient resiliency to hug the outer surface of the cylinder head regardless of any slight irregularities which this surface might have.

The sealing ring, as stated, is secured in place by being pressed into the counterbore. Further 25 assurance against displacement is obtained by having the cylindrical flange of the ring received in an arcuate slot 22 which cuts through a boss 23 formed in the counterbore to coact with the opposite ends of an arcuate inward extension 30 24 on the undersurface of the cylinder head to define the limits of rotation of the cylinder.

In assembling the lock, it is obvious that the cylinder must be inserted in the bore before the sealing ring is pressed in place. After the ring 35 has been secured in the counterbore, it acts to hold the cylinder in the bore; but inasmuch as the sealing ring of itself does not provide against forcible withdrawal of the cylinder as in an attempt to defeat the lock, additional cylinder 40 retaining means is provided. This cylinder retaining means consists of a cross pin 25 secured in the tubular extension 7 and received in an annular groove 26 in the adjacent portion of the cylinder extension 15.

45 The groove 26 is considerably wider than the diameter of the cross pin and these parts are so related that the pin is normally spaced from the sides of the groove to thus insure the maintenance of the desired snug engagement between 50 the cylinder head and the undersurface of the flange 18.

From the foregoing description taken in connection with the accompanying drawing, it will be readily apparent that this invention provides 55 means for effectively sealing the clearance between the cylinder and its bore against the entry of water and dirt which means, in conjunction with the usual keyhole cover, as in Patent No. 1,965,942, issued to Edward N. Jacobi, July 60 10, 1934, affords maximum protection for the internal structure of the lock against the corrosive effects of the elements.

What I claim as my invention is:

1. In a lock: a bored lock case; a lock cylinder in the bore; an annular flange at the mouth of the bore overlying the outer end of the cylinder; and a spring yieldingly urging the lock cylinder outwardly to hold its outer end firmly in engagement with the underside of said flange.
2. In a lock: a member having a bore; a lock cylinder mounted within the bore; a head on the lock cylinder positioned at the mouth of the bore; an annular flange at the mouth of the bore carried by said bored member and overlying the 70 head of the cylinder; and a spring urging the 75

lock cylinder outwardly to maintain the outer face of its head firmly in engagement with the undersurface of the flange.

3. In a lock: a member having a bore and a counterbore at the mouth of said bore; a lock cylinder disposed in said bore with its outer end in the counterbore; a ring secured in the counterbore; an inwardly directed annular flange on the ring extending over the outer end of the lock cylinder; and means yieldingly urging the lock cylinder outwardly of said bore to hold its outer end in firm engagement with the undersurface of said annular flange.

4. In a lock: a cylinder supporting member having a bore; a lock cylinder in the bore with the outer end thereof adjacent to the mouth of the bore; two independent means for holding the lock cylinder against withdrawal from the bore, one of said means comprising an annular inwardly directed flange carried by said supporting member at the mouth of the bore and overlying the outer end of the cylinder, the other of said means having a degree of lost motion in a direction axial to the cylinder so that the first of said designated means is normally primarily effective; and spring means urging the cylinder outwardly to hold the outer end thereof firmly against the underside of the annular flange.

5. In a cylinder lock of the type adapted for use on automobile door and deck handles where protection should be provided against the ingress of water into the bore in which the cylinder operates: a cylinder supporting member having a bore, the mouth of which is open; a lock cylinder mounted in the bore with its outer end adjacent to the mouth thereof; an inwardly directed annular flange carried by said bored member at the mouth of the bore and overlying the outer end of the cylinder; and spring means yieldingly urging the cylinder outwardly to hold the outer end of the cylinder firmly against the undersurface of the annular flange and thereby preclude the entrance of water and other foreign matter into the clearance between the cylinder and bore walls.

6. In a lock, the combination of: a cylinder supporting member having a bore and a counterbore at the mouth of the bore; a lock cylinder in the bore; an enlarged head on the outer end 50 of the cylinder disposed in the counterbore, said enlarged head having a smooth rounded outer surface; an annular insert secured in the counterbore and having a flange overlying the rounded outer surface of the cylinder head; and spring 55 means yieldingly urging the cylinder outwardly to maintain firm engagement between the cylinder head and said flange.

7. In a lock of the character described, the combination of: a member having a bore and a counterbore at the mouth of the bore; a cylinder mounted in the bore; a spring yieldingly urging the cylinder outwardly of the bore; and a retaining ring secured in the counterbore and having an inwardly directed annular thin-edged 65 flange overlying the outer end of the cylinder to engage the same and hold the cylinder against outward displacement by the spring, the thin-edged formation of the flange providing a degree of resiliency to insure snug engagement between the flange and the outer end of the cylinder for preventing the ingress of water and foreign matter between the cylinder and bore walls.
